EUGENE A. CLAUSS, OF PROVIDENCE, AND DAVID H. ADAMSON, OF CRANSTON, RHODE ISLAND.

BOOKBINDING.

1,426,043.

Specification of Letters Patent. Patented Aug. 15, 1922.

Application filed April 1, 1921. Serial No. 457,712.

To all whom it may concern:

Be it known that we, EUGENE A. CLAUSS and DAVID H. ADAMSON, citizens of the United States, residing at Providence and 5 Cranston, in the county of Providence and State of Rhode Island, respectively, have invented new and useful Improvements in Bookbinding, of which the following is a specification.

10 This invention relates to certain new and useful improvements in book binding, and the primary object thereof is to simplify the binding of the leaves or sheets, and to provide an improved structure wherein the flexible back is reinforced, and at the same time 15 permits of opening of the book so that the leaves will lie flat.

The invention briefly involves first the formation of the leaves or sheets into a pad 20 or stack; followed by the application of a flexible gum or cement to the back edges of the stack, and the application of an open mesh cloth to the gum or cement. Two or more holes are then formed, by drilling 25 through the pad, and tapes then passed through the holes with their ends cemented to the board or other material forming the book cover or sides, after which the book is finished in the ordinary manner of binding.

30 The invention also aims to provide a method of book binding which is simple and can be easily and quickly practiced, with the aim of economizing in the cost of the binding of books.

35 Further and other objects will be later set forth and manifested in the course of the following description.

In the drawings:

Figure 1 is a perspective view of a pile or 40 stack of leaves with the gum and mesh cloth applied thereto, and after being perforated;

Figure 2 is a fragmentary transverse section of the completed book; and

Figure 3 is a similar view with the book 45 in open position.

In proceeding in accordance with the present invention the leaves or sheets 1, are stacked, or arranged in a pile or pad formation as depicted in Figure 1 of the drawing,

50 ing, following which a gum or cement 2 is applied to the rear side edges of the pile or stack. Obviously the sheets will be held or

clamped in tight formation during the application of the gum or cement, the latter being of a flexible nature or having flexible 55 properties. A mesh cloth strip 3 is then applied to the gum or cement as shown in Figure 1 of the drawing, the strip being of the same size as the rear side edge of the stack or pile, or approximately of such size. Holes 4 are next drilled or otherwise formed through the pile or stack adjacent the rear side edge thereof, following which pieces of tape 5 are passed through the holes and have their ends extended outwardly toward 60 the back proper 9 and then extended inwardly and their terminals 6 cemented to the inner faces of the side boards or front and back covers 7 of the book. The usual finishing sheets 8 are applied to the inner faces of 70 the cover 7 and overlap the free ends of the tapes so as to conceal the latter and to also assist in securing same in position.

It will now be apparent that the tape acts as a reinforcement to the flexible backing 75 2—3, and at the same time allows of opening of the book so that the leaves will lie flat as depicted in Figure 3 of the drawing. The tape supports the pile or stack of the leaves or sheets both at the top and at the 80 bottom of the book, and acts as the only means of supporting the pile or stack from the cover 7. In this way a most simple and economical method of book binding is afforded, which dispenses with stitching or 85 the like, and at the same time enables the binding to be performed very expeditiously.

From Figure 2 of the drawing it will be seen that the stack of leaves or sheets are held at the rear thereof by the tape spaced 90 from the front and back 7—7 as well as from the back proper 9 which connect the side boards or front and back 7—7. Thus when the book is open as shown in Figure 3 the tapes move the back 3 of the stack up from 95 the back proper 9, thus permitting the leaves to lie flat when the book is open.

Having thus described our invention, what we claim as new and desire to secure by Letters Patent is:—

In a book, a stack of leaves having a cloth strip attached to the rear side edge thereof by a flexible adhesive and having perforations adjacent said edge, a cover having a

back and side boards connected thereto, and
tapes passed through the perforations and
having their ends turned outwardly and
then inwardly and their terminals cemented
5 to the side boards in a position to hold the
rear side edge of the stack spaced from the
back in both open and closed position of the
book.

In testimony whereof we have signed our
names to this specification in the presence of 10
two subscribing witnesses.

EUGENE A. CLAUSS.
DAVID H. ADAMSON.
